UNITED STATES PATENT OFFICE.

FRIEDRICH GALL, OF KIEL, GERMANY.

HAND MEMBER FOR DIVERS' ARMOR.

1,259,507.

Specification of Letters Patent. Patented Mar. 19, 1918.

Application filed May 20, 1914. Serial No. 839,707.

To all whom it may concern:

Be it known that I, FRIEDRICH GALL, a citizen of the German Empire, residing at Kiel, in the Kingdom of Prussia, Germany, Werk Ravensberg, Habsburg Ring, have invented certain new and useful Improvements in and Connected with Hand Members for Divers' Armor, of which the following is a specification.

10 This invention relates to divers' armor and consists of an improvement in the formation of the hand member or prosthetic hand. The essential feature of the invention consists in providing a rigid casing for 15 receiving the four fingers of a hand and another for the thumb, and movably connecting both these casings by a hollow pin joint which is pressure- and water-proof. The use of a rigid casing for the fingers of 20 the hand without the thumb has the advantage that divers' armor is adapted for greater depths than the arrangements hitherto employed, in which the fingers are each arranged in separate casings; in consequence 25 of the many small joints these cannot be made water- and pressure-proof without considerably affecting their mobility. The use of a pin joint instead of the ball joint hitherto employed has therefore the advantage 30 that a self-protected construction is obtained, while a ball joint must be incased in some suitable way, for example by means of a waterproof cloth or the like, which is exposed to wear and damage, more 35 particularly in the hand surfaces and also affects the mobility of the members.

The invention comprises a further improvement in that the finger casing is formed as a tool, *e. g.* it may end in a cutter. Further 40 the member may be provided with a device for holding tools which may be in the form of an annular eyelet located in the bend of the finger casing, so that tools in combination with the movable thumb case 45 may be held and used.

The invention will now be more particularly explained with reference to the accompanying drawings in some forms of construction by way of example.

50 Figures 1-3 show in side and plan view different forms of construction.

Fig. 4 is a vertical sectional view showing a form of the pin bearing;

55 Fig. 5 is a sectional view taken on the line 5-5 of Fig. 4.

In the forms of construction illustrated

a casing *a* is provided for the four fingers of the hand, and a casing *b* for the thumb, while the wrist joint *c* of the former may be made as a ball joint.

60

In the form of construction shown in Fig. 1, the front members of the four fingers lie in a part *d* of the casing arranged to correspond with the natural bend of the fingers, and connected with the part *a* of the casing by means of a continuous pressure- and water-proof pin bearing *e*, so that the part *d* can be moved in accordance with the natural movement of the fingers. The thumb casing *b* is arranged in similar manner.

70

In the form of construction shown in Figs. 2 and 3 the thumb casing *b* is also movably connected, but here the finger casing *a* is rigid and bent toward the front and also provided with a small flattened part *f* at the part which faces the thumb, which flattened part acts in conjunction with a similar surface on the thumb casing *b*, and thereby offers an abutment for the thumb in its movement in one direction. The other abutment *g* is provided on the fixed part of the joint body itself. This formation is preferable inasmuch as it allows of a scooping or cutting action to be exerted, and allows of objects being gripped and held by the movements of the thumb *b* together with the finger case *a*.

75

In the form of construction illustrated in Figs. 2 and 3 a ring *h* is provided in the angle which is formed by the bend of the finger case *a*, the opening of which ring may be used for attaching or inserting tools.

80

The end *i* of the finger case is preferably made as a cutting tool. One form of execution of the pin bearing *e* between the finger casing *d* and the hand casing *a* is shown in Figs. 4 and 5. Fig. 4 is a sectional side view of the joint and Fig. 5 a front view in section and on the line A-B of Fig. 4.

100

The finger casing *d* is flexibly connected with the hand casing *a* by means of a ball bearing *k* the outer ring of which fits in a boring of the casing *a*, while the inner ring is mounted upon a pin screwed into the finger casing *d*. In order to prevent a displacement of the members in axial direction, the hand member *a* is provided with a guiding ledge *m*. Outside the ball bearing is shut off waterproof by a cover *n* fixed to the face of the hand casing. The keeping apart of the two members is effected by a flexible

105

110

packing *o* which runs around the face of the hand member to which it is fixed. The movement of the member parts is limited by shoulders *p* and *q* provided upon the finger casing *d* which in their extreme position strike against the face of the hand casing *a*.

I declare that what I claim is:—

1. A hand member for divers' armor, comprising a rigid casing for the fingers; a device on said member adapted to receive tools and coöperating with said casing; a separate rigid casing for the thumb; said thumb and said device coöperating with each other to hold the tools; and pressure and water-tight joints pivotally connecting said casings.

2. A hand member for divers' armor, comprising a rigid casing for the fingers bent forwardly at right angles; a ring on said member adapted to receive tools and arranged in the angle of the casing; a separate rigid casing for the thumb and coöper-

ating with said ring; and pressure and water-tight hollow pin-joints pivotally connecting said casings.

3. A hand member for divers' armor, comprising a rigid casing for the fingers bent forwardly at right angles; a separate rigid casing for the thumb; and pressure and water-tight joints pivotally connecting said casings, one of the casings being formed into a cutting tool.

4. A hand member for divers' armor, comprising a rigid casing for the fingers; a separate rigid casing for the thumb; and pressure and water-tight hollow pin-joints pivotally connecting said casings, one of the casings being formed into a cutting tool.

In testimony whereof I affix my signature, in presence of two witnesses.

FRIEDRICH GALL.
